KNOCK-OUT TYPE ELECTRICAL INCLOSING BOX

Filed July 3, 1925

UNITED STATES PATENT OFFICE.

RALPH K. MASON, OF BANTAM, CONNECTICUT, ASSIGNOR, BY DIRECT AND MESNE ASSIGNMENTS, TO THE TRUMBULL-VANDERPOEL ELECTRIC MANUFACTURING COMPANY, OF BANTAM, CONNECTICUT, A CORPORATION OF CONNECTICUT.

KNOCK-OUT-TYPE ELECTRICAL INCLOSING BOX.

Application filed July 3, 1925. Serial No. 41,324.

On practically all electrical inclosing boxes, it is customary to provide a number of "knock-out" portions to form openings at desired locations, for the introduction of bushings, loom, conduits, troughs, or other conductors or conductor inclosures, or for the introduction within the inclosure of devices such as meters, fuse holders, etc. These "knock-out" portions are partly cut from the wall of the box or casing and one or more of them is knocked out to form the desired opening or openings. Difficulty is often encountered in removing these knock-out portions and there is danger of injuring the parts inclosed by the box or casing, even when a chisel is used to effect complete severing of the "knock-outs" from the wall. I have however provided a novel construction, whereby each "knock-out" is partly severed from the wall and a plurality of auxiliary "knock-outs" are provided adjacent the periphery of each main "knock-out", so that the strain when forming an opening in the wall, is localized at the auxiliary "knock-outs" when they are first removed, and removal of them serves to permit easy removal of the main "knock-out". In the preferred form of construction, the main "knock-out" is partly severed from the wall of the box or casing by an interrupted cut, each interruption of the cut leaving an integral neck which connects the "knock-out" with the wall, a portion of this wall, adjacent the periphery of the "knock-out" being partly cut from such wall to form a tongue which is integral with the aforesaid neck. Thus, this tongue may be laterally forced from the wall and used as means for breaking the neck, to facilitate removal of the "knock-out".

Different ways of carrying the invention into effect, are disclosed in the accompanying drawing, forming a part of this specification.

Figure 1 is an elevation of a box provided with the invention.

Figures 2 and 3 are sectional views on lines 2-2 and 3-3 of Fig. 1.

Figures 4, 5, 6 and 7 are elevations showing slight differences of construction.

In the drawing above briefly described, which illustrates the preferred details, the numeral 1 designates a wall of a malleable, stamped metal box or casing for inclosing an

electrical contrivance, said wall having a "knock-out" portion 2 of any desired configuration, partly cut therefrom by an interrupted cut 3, each interruption of said cut leaving a neck or bridge 4 which integrally joins the "knock-out" or main cut portion 2 to the surrounding portion of the wall 1. In most instances, I prefer that each reach of the interrupted cut 3, shall entirely sever a portion of the "knock-out" 2, from the adjacent part of the wall 1, and preferably the "knock-out" is laterally stamped into offset relation with the remainder of the wall as shown in Figs. 2 and 3, so as to later facilitate its removal.

A portion of the wall 1 adjacent each neck 4, or any desired number of the latter, is formed with a tongue 5 partly cut therefrom by a subsidiary cut 6 which preferably extends entirely through the wall, as shown in Fig. 2. This cut may either be uninterrupted from end to end as shown in Figs. 1, 2 and 6, or it may be an interrupted cut, as disclosed in Fig. 7. In either instance, each tongue or subsidiary cut portion 5 is left integrally joined to the bridge or neck 4. By preference, each cut 6 is formed in the "knock-out" or main cut portion as shown, so that the tongues or auxiliary cut portions 5 are within the confines of this "knock-out" and will not cause notches in the edge of the opening, when the main and subsidiary cut portions or "knockouts" are removed. This, however, is not essential.

In forms of boxes such as those disclosed in Figs. 1, 6 and 7, in which the "knock-out" has one of its edges formed by an edge of the wall 1, the invention may be carried out in numerous ways as will be clear from a comparison of these views. In this connection, however, it may be stated that the form of tongue shown in Fig. 7 is not restricted to a "knock-out" which extends entirely to an edge of the wall 1, but may be of course employed in connection with a "knock-out" of any other type, for instance, such as shown in Figs. 4 and 5. Moreover, it will be understood that the shape of the tongue 5 is immaterial.

Each tongue 5 constitutes an auxiliary "knock-out" at the periphery of the main "knock-out" 2, and it is an easy matter to break these auxiliary "knock-outs" loose from the box or casing, removal of each aux-

iliary "knock-out" forming an opening entirely through the wall. If desired, any opening thus formed may be used to receive the end of a screw driver, a pair of pliers or some other adequate tool which may be effectively used in entirely dislocating the main "knock-out" from the wall, without the necessity of excessive hammering and requiring no chiseling. When punching the auxiliary "knock-outs" laterally from their normal positions, only a slight force is necessary and this force is so localized that there is no danger of injuring parts within the box or casing, and in the forms of construction shown, it will be seen that when any tongue 5 is forced laterally, it may be effectively used as means to break the neck 4 with which it is integral. When the cut 3 extends entirely through the wall as in the present instance, breaking of the necks 4 by manipulation of the tongues 5, serves in some forms of construction, to entirely separate the main "knock-out" from the wall, and in other cases (Fig. 1 for instance), the connection between the "knock-out" and the wall is at least so weakened that said "knock-out" may be easily removed without trouble and without danger of injuring any parts within the casing or box. At this point, it may be explained that the tongues or auxiliary "knock-outs" 5 of Fig. 1 are so located that they may be easily gripped with a pair of pliers and wrenched or twisted loose. If mere lateral forcing of any of the other tongues or auxiliary "knock-outs" does not break them loose from the wall, they may either be worked back and forth or gripped with a pair of pliers and twisted. In the form of construction shown in Fig. 7, either end of the tongue 5 may be forced laterally in one direction and this will cause opposite movement of its other end, so that it will easily twist off.

By employing any form of construction herein disclosed or any analogous form, in which a main "knock-out" and an auxiliary "knock-out" or a plurality of them, are associated in substantially the unique manner disclosed, a marked advance is made, as not only is the difficulty of removing the "knock-outs" reduced, but there is no danger whatever of injuring any parts inclosed by the box or casing. In the preferred construction, several species of which have been shown, the auxiliary "knock-outs" form the sole means of connecting the main "knock-out" with the box or the like, but this is not in all instances necessary, as even if the cuts 3 did not entirely extend through the wall 1, removal of the auxiliary "knock-outs" would form openings to effectively weaken the connection between the main "knock-out" and the wall, so that said main "knock-out" could be easily removed.

It is to be understood that the term "knock-out" does not necessarily have the restricted meaning of a portion which is actually knocked out by a blow or blows, but this term is used in a sufficiently broad sense to be applicable to a portion which is twisted out, pried out or otherwise removed.

I claim:

1. A metal electrical inclosing box having a main cut portion to provide an opening when removed, said main cut portion being normally retained in place by an uncut bridge, and a subsidiary cut portion contiguous to the uncut bridge and providing means for breaking said bridge before removing the main cut portion. 80

2. A metal electrical inclosing box having a main cut portion to provide an opening when removed, an uncut supporting portion normally connecting said main cut portion with the adjacent portion of the box, and a subsidiary cut partly surrounding said uncut supporting portion, providing a twistably removable portion for severing said uncut portion by a localized twisting operation. 85

3. A metal electrical inclosing box having a main cut portion positioned to form a notch in an edge of the inclosure when removed, an uncut supporting portion normally connecting said main cut portion with the adjacent portion of the box, and a subsidiary cut partly surrounding said uncut supporting portion, providing a twistably removable portion for severing said uncut portion by a localized twisting operation. 90

4. An electrical inclosing box having a "knock-out" portion partly severed from one of its walls by an interrupted cut, the interruption of said cut leaving a narrow neck integrally connecting the "knock-out" portion with the contiguous portion of the wall, said wall having a restricted tongue partly cut therefrom and integral with said neck, the ends of the tongue-forming-cut being disposed substantially at opposite sides of said neck and substantially at the peripheral edge of said "knock-out" portion. 100

5. An electrical inclosing box having a "knock-out" portion partly severed from one of its walls by an interrupted cut, the interruption of said cut leaving a narrow neck integrally connecting the "knock-out" portion with the contiguous portion of the wall, said "knock-out" portion having a restricted tongue partly cut therefrom and integral with said neck, the ends of the tongue-forming-cut being disposed substantially at opposite sides of said neck and substantially at the peripheral edge of said "knock-out" portion. 110

In testimony whereof I have hereunto affixed my signature.

RALPH K. MASON.
